UNITED STATES PATENT OFFICE.

RANSOM C. WRIGHT, OF PHILADELPHIA, PENNSYLVANIA, AND FRANK E. STEBBINS, OF WASHINGTON, DISTRICT OF COLUMBIA.

CONSTRUCTION OF CAR-TRUCKS.

No. 860,955.

Specification of Letters Patent.

Patented July 23, 1907.

Application filed October 4, 1902, Serial No. 125,890. Renewed October 18, 1904. Serial No. 228,926.

To all whom it may concern:

Be it known that we, RANSOM C. WRIGHT and FRANK E. STEBBINS, citizens of the United States, residing, respectively, at Philadelphia, in the county 5 of Philadelphia and State of Pennsylvania, and at Washington, District of Columbia, have invented certain new and useful Improvements in the Construction of Car-Trucks, of which the following is a specification.

The object of our invention is the production of a 10 car truck frame which can easily and cheaply be constructed and repaired in the ordinary car shop without the use of special tools, machinery, or appliances; which shall have a transom adapted to support great weights; and which shall have pedestals that can be 15 detached when worn or injured and others substituted therefor.

With these main ends in view our invention consists in certain novelties of construction and combinations of parts hereinafter set forth and claimed.

20 The accompanying drawings illustrate one complete example and one modification of the physical embodiment of our invention constructed according to the best modes we have so far devised for the practical application of the principle.

25 Figure 1 is a side view in elevation of the truck frame with wheels, journal boxes, and springs in place above the journal boxes. Fig. 2 is a half top plan view of Fig. 1 showing the method of strengthening the transom. Fig. 3 is a section of Fig. 1 on line $x-x$ 30 through the pedestal neck and side beams. Fig. 4 is a section of Fig. 1 on line $v-v$. Fig. 5 is a side view in elevation of a modification. Fig. 6 is a partial top plan view of Fig. 5. Fig. 7 is a section of Fig. 6 taken in a line between the transoms.

35 Referring to the figures of the drawings, the numeral 1 designates the outside flanged beam of the frame; 2, the inside flanged beam; 3, 3, the transom beams, also flanged; 4, 4, connection angles which serve by means of rivets to secure the ends of the transoms to the inside flanged beams; 5, bottom stiffening plates which are riveted to the lower flanges of the transoms at the ends and to the flanges of the side pieces; 6, cast metal pedestals; 7, the pockets for the springs; 8, pedestal necks; 9, the top flanges of the necks; 10, the bottom flanges of the necks; 11, the webs of the necks, located between the top and bottom flanges; 12, the top perpendicular flanges over or adjacent the spring pockets; 12', bottom flanges; 13, rivets which secure the webs of the pedestals and the ends of the outside and inside flanged beams; and 14 are rivets through the flanges of the neck at the top and bottom thereof and the flanges of the beams.

In the example illustrated by Figs. 1, 2, 3, and 4 the numeral 15 designates a channel beam extending from side to side of the frame; 16, rivets securing the 55 channel beam to the transom beams, said rivets being passed through the web of the channel beam and the top flanges of the transom beams; 17, rivets securing the channel beam to the top flanges of the outside and inside flanged beams which constitute a side; 18, a 60 hole in the channel beam; 19 wheels and axles; 20, the journals; 21, the spiral springs resting upon the journal boxes and bearing against the bottoms of the pockets in the pedestals; and 22, are the journal boxes.

Referring to Figs. 5, 6, and 7, the numeral 35 designates the widened top flange of the inside flanged beams; 36, rivets securing the ends of the transoms to the flange; 37, filling pieces hooking over the outer and inner side pieces, as shown in Fig. 7, so as to take the shearing strains off the rivets; and 38 are rivets 70 through the filling pieces and inner and outer flanged beams.

Referring to both examples, 39 designates the strengthening flanges of the outer pedestal legs or jaws; 40, spacing thimbles; 41, tie bolts; 42, nuts on the 75 bolts; 43, the outer and inner bearing flanges of the jaws which engage recesses in the vertical sides of the journal boxes; and 43' in Fig. 1 are the bearings on flanges 12' for the heads of the bolts.

The methods of assembling the several parts of the 80 frames, as illustrated, will readily be understood from an inspection of the drawings and, therefore, need not be specifically described.

From the foregoing description taken in connection with the drawings it is obvious that we have produced 85 car truck frames which fulfil all the conditions set forth as the end and object of our invention.

In physically embodying our improvements, it is, of course, to be understood that modified modes of construction in details may be adopted and followed 90 without constituting substantial departures.

What we claim as new and desire to secure by Letters Patent, is:—

1. The combination in a truck frame of sides each comprising two flanged beams; cast metal pedestals having 95 necks secured on the perpendicular ends of each side, and a transom or transoms adapted to support a car body and uniting the sides adjacent their centers.

2. The combination in a truck frame of sides each comprising two flanged beams; cast metal pedestals having 100 necks secured on the perpendicular ends of each side, and a transom or transoms adapted to support a car body and uniting the sides adjacent their centers; each of said cast metal pedestals having top and bottom flanges riveted to the flanges of the said two flanged beams.

3. The combination in a truck frame of sides each com-

- prising two flanged beams; cast metal pedestals having necks secured on the perpendicular ends of each side, and a transom or transoms adapted to support a car body and uniting the sides adjacent their centers; each of said pedestals having the web of its neck riveted to the said two flanged beams.
4. The combination in a truck frame of sides each comprising two flanged beams; cast metal pedestals having necks secured on the perpendicular ends of each side, and a transom or transoms adapted to support a car body and uniting the sides adjacent their centers; each of said pedestals having a spring pocket to strengthen the head of the pedestal adjacent the ends of the two flanged beams.
5. The combination in a truck frame of sides each comprising two flanged beams; cast metal pedestals having necks secured on the perpendicular ends of each side, and a transom or transoms adapted to support a car body and uniting the sides adjacent their centers; each of said pedestals having a spring pocket and a strengthening flange, as 12, adjacent the pocket.
10. The combination in a truck frame of sides each comprising two flanged beams; cast metal pedestals having necks secured on the perpendicular ends of each side, and a transom or transoms adapted to support a car body and uniting the sides adjacent their centers; each of said pedestals having the web of its neck interposed between the ends of the said two flanged beams and secured by rivets.
15. The combination in a truck frame of sides each comprising two flanged beams; cast metal pedestals having necks secured on the perpendicular ends of each side, and a transom or transoms adapted to support a car body and uniting the sides adjacent their centers; each of said pedestals having a strengthening flange over the head of the pedestal and another for the outer jaw, and the neck provided with flanges which are riveted to the flanges of a side.
20. The combination in a truck frame, of sides each comprising two flanged beams cut off through the webs and flanges; cast metal pedestals secured on to the ends of each side; and a transom comprising two flanged beams uniting the sides adjacent their centers.
25. The combination in a truck frame, of sides each comprising two flanged beams; cast metal pedestals secured on to the ends of each side; a transom comprising two flanged beams uniting the sides adjacent their centers; and a flanged beam secured to the two flanged transom beams.
30. The combination in a truck frame, of sides each comprising two flanged beams; cast metal pedestals secured on to the ends of each side; a transom comprising two flanged beams uniting the sides adjacent their centers; each of the said pedestals having a strengthening flange over the head of the pedestal and another for the outer jaw, and the neck provided with flanges which are riveted to the flanges of a side.
35. The combination in a truck frame, of sides each comprising two flanged beams; cast metal pedestals secured on to the ends of each side; a transom comprising two flanged beams uniting the sides adjacent their centers; and a flanged beam secured to the two flanged transom beams.
40. The combination in a truck frame, of sides each comprising two flanged beams; cast metal pedestals secured on to the ends of each side; a transom comprising two flanged beams uniting the sides adjacent their centers; and a flanged beam secured to the two flanged transom beams.
45. The combination in a truck frame, of sides each comprising two flanged beams; cast metal pedestals secured on to the ends of each side; a transom comprising two flanged beams uniting the sides adjacent their centers; and a flanged beam secured to the two flanged transom beams.
50. The combination in a truck frame, of sides each comprising two flanged beams; cast metal pedestals secured on to the ends of each side; a transom comprising two flanged beams uniting the sides adjacent their centers; and a flanged beam secured to the two flanged transom beams and to the sides.
55. The combination in a truck frame, of sides each comprising two flanged beams; cast metal pedestals secured on to the ends of each side; a transom comprising two flanged beams uniting the sides adjacent their centers; and a channel beam secured by rivets to the top of the two flanged transom beams.
60. The combination in a truck frame, of sides each comprising two flanged beams; cast metal pedestals secured on to the ends of each side; a transom comprising two flanged beams uniting the sides adjacent their centers; and a channel beam secured to the two flanged transom beams and to the sides.
65. A truck frame having metallic sides and flanged transom beams, and a flanged beam secured to the flanges of the transom beams.
70. A truck frame having metallic sides and flanged transom beams, and a flanged beam secured to the top of the transom beams and the sides.
75. A truck frame having flanged sides each having two top flanges and transom beams and a flanged beam secured to the transom beams and the flanges of the sides.
16. A truck frame having flanged sides and flanged transom beams, and a channel beam secured to the top of the transom beams and the sides.
17. A truck frame having flanged sides and flanged transom beams, and a flanged beam secured to the transom beams and sides.
18. A truck frame having sides comprising two flanged beams, transom beams with flanges, and a flanged beam secured to the transom beams and sides.
19. A truck frame having metallic sides and flanged transom beams, and a straight flanged beam with upwardly projecting flanges secured to the flanged transom beams and sides.
20. A truck frame having sides each comprising two channel beams, two flanged transom beams, and a flanged beam secured to the flanges of the transom beams and to the flanges of the channel side beams.
21. A truck frame having metallic sides, two flanged transom beams with flanges extending outwardly, and a flanged beam having its web riveted to the flanges of the transom beams.
22. A truck frame having flanged sides and transoms, a plate, as 5, secured to the sides and transoms at the bottom, and a flanged beam secured to the transoms and sides at the top.
23. A truck frame having sides each comprising two channel beams, two channel transom beams, and a flanged beam having its web secured to the flanges of the transom channels and its ends to the sides.
24. A truck frame having sides each comprising two channel beams, two channel transom beams, and a horizontal top metallic element with flanges riveted to the side channels and to the flanges of the transom channels.
25. A truck frame having sides each comprising two channel beams cut off square at their ends; cast metal pedestals secured between the ends of the channel beam sides at their ends and extending over the journal boxes, a transom or transoms uniting the sides adjacent their centers; and means for stiffening the frame where the transom ends join the sides.
26. The combination in a truck frame, of sides each comprising two flanged beams; cast metal pedestals each having a neck secured to the perpendicular end of a side; and a transom or transoms adapted to support a car body uniting the sides adjacent their centers; each of said cast metal pedestals having a web and top flanges riveted to the webs and top flanges of said two flanged beams.
27. The combination in a truck frame, of sides each comprising two flanged beams; cast metal pedestals each having a neck secured to the perpendicular end of a side; and a transom or transoms adapted to support a car body and uniting the sides adjacent their centers; each of said cast metal pedestals having a web and lower flanges riveted to the webs and lower flanges of said two flanged beams.
28. The combination in a truck frame, of sides each comprising two channel beams; cast metal pedestals each having a neck secured to the perpendicular end of a side; and a transom or transoms adapted to support a car body and uniting the sides adjacent their centers; each of said cast metal pedestals having a web and flange or flanges riveted to the webs and flange or flanges of the said two flanged beams, a bearing flange adjacent the neck, a bearing or seat for a spring, and an outer rigid pedestal jaw with a flange adapted to bear against the journal box; means being provided for closing the opening between the jaws through which the journal box is inserted and withdrawn.
